UNITED STATES PATENT OFFICE.

GEORG KARL KNAPP, OF NUEREMBERG, GERMANY.

ELECTRICAL STARTER FOR EXPLOSIVE ENGINES.

Application filed October 11, 1920. Serial No. 416,284.

To all whom it may concern:

Be it known that I, GEORG KARL KNAPP, a citizen of Germany, residing at Nuremberg, Germany, have invented certain new and useful Improvements in Electrical Starters for Explosive Engines; and I do hereby declare the following to be a full, clear, and exact description of the invention, such as will enable others skilled in the art to which it appertains to make and use the same.

My invention relates to improvements in electrical starters for explosive engines, and more particularly in starters comprising a motor-dynamo having two armature windings one of low resistance and few turns and the other one of a greater number of turns and higher resistance. One of the objects of the improvements is to provide a starter of this type which when operated as a motor for starting the engine is adapted to produce a high torque at comparatively low speed, and which when operating under no load does not run at excessive speed. With this and other objects in view my invention consists in the matters to be described hereinafter and particularly pointed out in the appended claims. For the purpose of explaining the invention several examples embodying the same have been shown in the accompanying drawings, in which the same letters of reference have been used in all the views to indicate corresponding parts. In said drawings,—

Fig. 1, is a plan view of an explosive engine and a starter disposed on an automobile.

Fig. 2, is a diagrammatical view illustrating the circuits of the starter.

Figs. 3 and 4, show a modification of the system, Fig. 3 showing the same when operating as a motor and Fig. 4 when operating as a generator, and

Fig. 5, is a diagrammatical view showing the windings as disposed on field poles.

As appears more particularly from Fig. 1 my improved system consists of an explosive engine, *a*, motor-dynamo *d* connected with the crank shaft of the engine by a suitable gearing *c*, and a secondary battery *e*. As shown, the whole system is mounted on an automobile *b*. In the preferred form the gearing *c* is in the form of a change speed gearing, and good results

have been obtained by providing a frictional change speed gearing or a gearing of the epicyclic type.

The electrical part of the system consists of a single armature having two armature windings *f* and *f'* shown separately in the figure for convenience of illustration, the armature winding *f* being of low resistance and few turns to produce a large torque when the machine is used as a motor to start the engine and the winding *f'* having a high resistance and a greater number of turns for supplying the necessary voltage to charge the battery *e*. The motor-dynamo is provided with two field windings *l* and *p*, the winding *l* being of low resistance and few turns and the winding *p* of higher resistance and many turns. If the system operates as a motor for starting the engine a switch *i* is set in the position shown in dotted lines, and the current taken from the + terminal of the storage battery *e* passes over a lead *g*, the motor winding *f*, a lead *h*, the switch *i*, a lead *k*, the series winding *l*, to the ground or frame work of the engine indicated by the minus sign, and back to the minus terminal of the secondary battery. Furthermore the generator winding *f'* is closed over a lead *m*, a resistance *n*, a lead *o*, the field winding *p* connected in this case in series, and a lead *q*. Therefore, the motor field is excited by both field windings *l* and *p*, so that a strong torque is produced. In addition the generator winding *f'* and its circuit have a braking action resulting in a reduction of the velocity of the armature, which is important because for starting the engine a low speed is required. Furthermore the counter-electromotive force within the motor winding is small and the current flowing through the same is large, which results in a strong torque. The torque is at its maximum at the beginning of the starting operation and when the power required for starting the engine is high. As the velocity of the motor increases the current produced in the armature winding *f'* and energizing the field winding *p* gradually causes an increase of the strength of the field. Therefore the velocity of the system is not increased upon a reduction of the load to such an extent as in the case of a pure series motor, the system having in a certain degree a character similar to that of a com-

5 pound motor which upon a reduction of the load assumes more and more the character of a shunt wound motor. Furthermore by increasing the intensity of the field by means of the winding p the torque is increased. Experiments have shown that practically this increase amounts to as much as from 20 to 25% though the current supplied by the storage battery is not increased.

10 It will be understood that the current flowing through the winding f^1 and resulting in an increase of the intensity of the field depends on the value of the resistance n . If the resistance is high, for example 30 ohms, the current flowing through the field winding p varies in practical constructions according to the number of revolutions from 1.0 to 1.5 amperes. As the number of the turns of the coil p is high the field is considerably increased, as has been shown by experiments. However, the current flowing through the circuit of the winding f^1 is practically not more than from .5 to 1.0% of the motor current, so that the energy required 25 for revolving the winding f^1 is small. In any case the increase of the torque caused by strengthening the field is considerably higher, so that the power and the efficiency of the system are increased. Furthermore, 30 experiments have shown that by reducing the resistance n the torque is increased, but simultaneously the number of revolutions is reduced, so that the power and the efficiency are reduced. It will therefore be understood that the value of the resistance n is important in my improved system.

40 After the explosive engine has been started the switch i is set in the position shown in full lines, whereby the conductors h and k are interrupted, the resistance n is short-circuited, and the conductor h is connected with the + terminal of the generator winding f^1 by a lead m^1 . Now the system operates as a generator. A current flows through the 45 armature f^1 , the lead m^1 , the switch i , the lead o , the field winding p , the lead q , and to the - terminal of the armature winding. The main current flows from the ground or the machine frame over a lead s , a series 50 field coil r for regulating the voltage, the armature winding f^1 , the lead m^1 , the switch i , the conductor h , the motor winding f , the lead g , the battery e , and back to the ground or the machine frame. The first named current is used for energizing the field. For 55 producing the voltage for charging the battery both armature windings f and f^1 are operative, the armature current flowing through the winding f^1 in the same direction as before and through the winding f in the opposite direction as compared to the motor action.

60 Preferably the conductor s includes an automatic or hand operated switch t by means 65 of which the dynamo is disconnected from

the storage battery e when the explosive engine is at rest, in order that the dynamo is not accidentally operated as a motor. The secondary battery may be connected by a switch v to current consumers such as a 70 lighting system.

When operating the system as a generator the field energizing circuit f^1 , p does not include the armature winding f . I have found this to be an important feature of my 75 invention, because thereby the energizing of the field is made reliable which is particularly important in my improved system where the field must be energized at low speed. As is known in the art, the energizing 80 of an electric machine is more reliable where the field circuit has a low resistance, particularly where the number of revolutions is low. In addition the resistance at the brushes interferes with the energizing 85 of the field. Therefore a system in which only two brushes are included, in the present case those of the winding f^1 , is preferable as compared to a system in which also the brushes of the winding f are included in 90 the said circuit, so much the more as the last named brushes are those of the motor winding which ordinarily do not make as good contact as the brushes of the generator winding f^1 .

95 In the example shown in Figures 3 and 4 the system is different from that shown in Figs. 1 and 2 in the following respects: The polarity of the low resistance or motor winding f^2 and the high resistance or generator winding f^3 is the reverse from that shown in Figs. 1 and 2. To the brush of the armature winding f^2 two leads q^2 and s^2 are connected, the lead q^2 providing a connection with the high resistance field winding p^2 and the lead s^2 providing a connection with a series field coil r^2 and through a lead s^3 and a switch t^2 with a lead q^2 connected to the + terminal of the secondary batter e^2 and with a switch r^2 . The switch r^2 is also adapted to make 110 connection with the winding p^2 through a lead o^2 . In a lead m^2 connecting the minus terminal of the generator winding f^3 with the lead o^2 a resistance n^2 is included. The minus terminal of the winding f^3 is in constant connection by a lead m^3 with the + terminal of the winding f^2 the minus terminal of which is connected by a lead h^2 with the low resistance winding f^2 .

115 For starting the engine the switch i^2 is set in the position shown in Fig. 3 for connecting the leads g^2 and h^2 . Thereby the armature winding f^2 and the field winding f^2 are connected in series and current is supplied thereto from the battery e^2 . The armature winding f^3 is in a circuit including the resistance n^2 and the field winding p^2 whereby the field of the motor part of the machine 125 is strengthened.

130 When the parts of the system are thus con-

5 nected the current passes from the + terminal of the battery e^2 over $g^2, i^2, h^2, f^2, k^2, l^2$, frame of the engine, and back to the - terminal of the battery, the current passing 10 through the field winding l^2 in the direction from the bottom to the top thereof as is indicated by the arrow shown in connection with the winding. The rotating armature builds up a current passing through the high 15 resistance armature winding f^3 , the + brush thereof, through g^2, p^2, o^2, n^2, m^2 , and to the - brush of the winding f^3 , said current passing through the winding p^2 in the direction from the bottom to the top thereof 20 15 as is indicated by the arrow shown in connection with the said winding. Therefore the windings p^2 and l^2 combine to strengthen the field as has been described with reference to the example shown in Figs. 1 and 2. 25 20 After the engine has become self operating the switches t^2, i^2 are set in the position shown in Fig. 4. Now the field winding l^2 and the series field or regulating coil r^2 are energized so as to take part in the production 30 25 of the field. A current is furnished to the battery e^2 which passes from the - terminal of the battery and the frame of the engine over $l^2, h^2, f^2, n^2, f^3, s^2, r^2, s^3$ and the switch i^2 to the + terminal of the battery, 35 30 the current passing through the windings l^2 and r^2 from the top to the bottom thereof. Therefore the current passes through the winding l^2 in a direction opposite to that described with reference to Fig. 3 and the 40 35 motor action of the system. The current passing through the high resistance field coil p^2 has the same direction as before, that is from the bottom to the top thereof, said current passing from the + terminal of the 45 40 armature winding f^3 over $g^2, p^2, o^2, i^2, h^2, m^2$, and back to the minus brush of the winding f^3 .

From the foregoing it will be understood 45 50 that the system embodies all the advantages described with reference to Figs. 1 and 2, and in addition it is preferable because the number of the turns of the series field r^2 can be reduced by the number of the turns of the low resistance winding l^2 , which results in a saving in the length of the lead 55 60 material and in a saving of space.

As is known to those skilled in the art, the field windings are uniformly distributed on all the field poles. Therefore the windings p^2, r^2 , and l^2 must be divided into so many sectional windings as there are field poles, so that one sectional winding p^2, r^2 , and l^2 can be placed on each of the poles. For example, if the machine is constructed 65 70 with four poles, four sectional windings of each of the windings p^2, r^2 and l^2 , that is twelve windings must be disposed on the said poles.

This however is objectionable by reason 65 70 of the great number of conductors between

the sectional windings, because it is difficult to make the proper connections with reference to the sense in which the coils are wound, and because there is but little room for disposing all the conductors. Therefore, 70 I prefer the arrangement of the coils shown in Fig. 5.

In accordance with the cooperation of the field and regulating windings described above the motor winding l^2 and the regulating winding r^2 are disposed on the same poles, and the generator winding p^2 is disposed on the intermediate poles. 75

In the example shown in Fig. 5 the machine is constructed with four poles and the windings, p^2, r^2 , and l^2 are respectively divided into two sectional coils indicated in the said figure by the reference characters $p^{21}, p^{22}, r^{21}, r^{22}$, and l^{21}, l^{22} . The winding p^{21} is disposed on the pole v^1 and the winding p^{22} on the opposite pole v^2 , and each of the other poles w^1 and w^2 carries a sectional coil l^{21} and r^{21} and l^{22} and r^{22} respectively. 80 85

By thus disposing the windings instead of twelve coils only six are necessary whereby the work of winding the coils is considerably reduced. In addition the number of the connections between the coils is reduced, and the disposition of the coils is comparatively simple, so that the correct connections can 90 95 more easily be made.

The operation of my improved system is as follows: When operating the system as a motor and with normal load the same ampere-turns are produced by the windings l^{21}, l^{22} and p^{21}, p^{22} . The connections between the windings are such that each of the windings l^{21} and l^{22} produces a north pole, while each of the windings p^{21} and p^{22} produces a south pole. Therefore the result is the same 100 105 as when uniformly distributing the coils of the windings p^2 and l^2 on all the poles.

When operating the machine as a generator the polarity of the coils p^{21} and p^{22} is the same as before and they produce 110 south poles. Also the polarity of the coils l^{21} and l^{22} is reversed and they tend to produce south poles, being assisted by the coils r^{21} and r^{22} of the series field or regulating winding. 115

But the number of the ampere turns of the coils p^{21} and p^{22} considerably exceeds that of the coils r^{21}, l^{21} and r^{22}, l^{22} and the flux of the lines of forces built up by the coils p^{21} and p^{22} will overcome the flux of 120 the coils r^{21}, l^{21} , and r^{22}, l^{22} and the lines of force will pass through the coils r^{21}, l^{21} and r^{22}, l^{22} . Therefore since the resultant lines of flux pass into the poles surrounded by the coils r^{21}, l^{21} and r^{22}, l^{22} from the magnet frame of the machine and pass out of these poles through the air gap, they will 125 be north poles.

Therefore the leakage of the machine operating as a generator is materially in- 130

creased, whereby the voltage is reduced particularly at high speed of the machine.

I claim:

1. In a starting device for prime movers 5 a series motor, a battery connected to drive the motor, a generating coil carried by the motor armature, and a coil connected across the generating coil and disposed to assist the motor field.
- 10 2. In a starting device for prime movers, a dynamotor having a high resistance and a low resistance field, and a high resistance and a low resistance armature winding, a storage battery, means for connecting the 15 low resistance armature and low resistance field in series with the battery to run as a motor, and means for connecting the high resistance field across the high resistance armature as a generator to assist the motor 20 field.
- 15 3. In a starting device for prime movers, a dynamotor having a high resistance and a low resistance field, and a high resistance and a low resistance armature winding, a storage battery, means for connecting the 25 low resistance armature and low resistance field in series with the battery to run as a motor, means for connecting the high resistance field and high resistance armature 30 as a generator to assist the motor field, and means for connecting the armatures in series to charge the battery.
- 20 4. An electric starter for prime movers comprising a motor-dynamo having an armature provided with two armature windings of different numbers of turns and field windings one connected in shunt across the terminals of the armature winding of greater number of turns, a storage battery, 35 means to connect said armature winding of smaller number of turns and said field winding which is not connected in shunt with said storage battery for operation by the current supplied by the battery, and means 40 to connect both of said armature windings and battery in series with one another for operation of the system as a generator.
- 25 5. An electric starter for prime movers comprising a motor-dynamo having an armature provided with two armature windings of different numbers of turns and field windings, a resistance, a circuit including in series said armature winding of greater number of turns, one of said field windings, and 50 said resistance, a storage battery, means to connect said armature winding of smaller number of turns and said winding not included in said circuit with said storage battery for operation by the battery, and means 55 to connect both of said armature windings and battery in series with one another for operation of the system as a generator.
- 30 6. An electric starter for prime movers comprising a motor-dynamo having an armature provided with two armature windings of different numbers of turns and field windings, a storage battery, means to connect said armature winding of smaller number of turns and said winding not included in said circuit with said storage battery for operation by the battery, and means 60 to connect both of said armature windings and battery in series with one another for operation of the system as a generator.
- 35 7. An electric starter for prime movers comprising a motor-dynamo having an armature provided with two armature windings of different numbers of turns and field windings one connected in shunt across the terminals of the armature winding of greater number of turns, a storage battery, means to connect said armature winding of smaller number of turns and said winding which is not connected in shunt with said storage battery for operation by the current supplied by the battery, and means to connect both of said armature windings, the field winding which is not connected in shunt and battery 80 in series with one another for operation of the system as a generator.
- 40 8. An electric starter for prime movers comprising a motor-dynamo having two armature windings of different numbers of turns, field windings of different numbers of turns, and a regulating coil arranged to build up a field, said field winding of greater number of turns being connected in shunt across the terminals of said armature winding of greater number of turns, a storage battery means to connect said armature and field windings of smaller numbers of turns in series with said storage battery for operation by the current supplied by the battery, 95 and means to connect both of said armature windings, said field winding of smaller number of turns, regulating coil and battery in series with one another for operation of the system as a generator.
- 45 9. An electric starter for prime movers comprising a motor-dynamo having an armature provided with two armature windings of different numbers of turns, field windings of different numbers of turns, and a regulating coil arranged to build up a field, said field winding of greater number of turns being connected in shunt across the terminals of said armature winding of greater number of turns, and said field winding 100 of smaller number of turns and regulating winding being made in sections disposed respectively on the same magnet pole and the field winding of greater number of turns being made in sections disposed respectively 105 on poles located between the poles carrying the sections of the field winding of smaller number of turns and of the regulating coil, a storage battery, means to connect said armature and field windings of smaller numbers 110
- 50 115
- 55 120
- 60 125
- 65 130

of turns in series with said storage battery for operation by the current supplied by the battery, and means to connect both of said armature windings, said field winding of 5 smaller number of turns, regulating coil and battery in series with one another for operation of the system as a generator.

In testimony whereof I hereunto affix my signature in the presence of two witnesses.

GEORG KARL KNAPP.
